UNITED STATES PATENT OFFICE.

CHARLES KNAPP, OF NEW YORK, N. Y.

DESIGN FOR A RING.

SPECIFICATION forming part of Design No. 24,690, dated September 24, 1895.

Application filed July 9, 1895. Serial No. 555,934. Term of patent 7 years.

To all whom it may concern:

Be it known that I, CHARLES KNAPP, a citizen of the United States, and a resident of New York, county and State of New York, have 5 invented and produced a new and original Design for Rings, of which the following is a specification, reference being had to the accompanying drawings, forming part of this specification, wherein—

10 Figure 1 is an enlarged view showing the design arranged around the head of the ring, and Fig. 2 a perspective view of the ring.

15 The leading feature of my design consists of a composition of artistically-curved volutes combined with consoles and helices into a plastic ornament surrounding the head of a ring and connecting it to the band, whereby the effect of the setting is greatly increased. For this purpose I also use colored rosettes 20 set between the curves of the ornament.

25 The design is composed in the following manner: A volute *a*, supposed to rise from the band of the ring, connects through a console *b* on one side and through a helix *c* on the other side with two other volutes *d* and *e*, appearing to support the head of the ring. Beyond volute *d* the heads of two other simi-

larly-shaped volutes *d'* and *d''* appear, adjoining the edge of the head of the ring, one beyond the other, completing the ornament. 30 The ground is matted and four-pointed rosettes, three on each side, are set in the fields between the curves. One of these rosettes is set in center of volute *a*, the second in the field between the console *b* and helix *c*, and 35 the third in the field between the two volutes *d* and *e*. This rosette, located nearest to the head of the ring, is the largest, and the one located in center volute *a* is the smallest. Their design does, however, not differ in any 40 feature. The ornament is symmetrically arranged. The edges may be scalloped and the faces dotted or smoothly finished.

I claim—

10 The design for a ring as herein shown and 45 described.

In witness that I claim the design described in the foregoing specification I have signed my name in the presence of two subscribing witnesses.

CHAS. KNAPP.
